UNITED STATES PATENT OFFICE.

JOSEPH PETER GERING, OF SCHRAG, WASHINGTON.

SPARK-ADJUSTER FOR EXPLOSIVE-ENGINES.

1,092,255.

Specification of Letters Patent. Patented Apr. 7, 1914.

Application filed February 10, 1913. Serial No. 747,222.

To all whom it may concern:

Be it known that I, JOSEPH PETER GERING, a citizen of the United States, residing at Schrag, in the county of Adams and State of Washington, have invented certain new and useful Improvements in Spark-Adjusters for Explosive-Engines, of which the following is a specification.

The object of the present invention is a device which is connected to the engine shaft and the spark regulating lever and which by its rotation adjusts the spark regulating lever according to the speed of the engine.

Other objects and advantages of my invention will become more fully apparent from the following description.

Referring to the accompanying drawings: Figure 1 shows part of an explosive engine in its state of rest with the spark retarded for starting. Fig. 2 is a similar view with the spark advanced automatically during the running of the engine at a high rate of speed. Figs. 3, 4 and 5 are detail views of the adjusting mechanism on an enlarged scale.

Referring specifically to the drawing, 10 indicates a shaft connected with the main shaft of the engine by a belt 11. To the outer free end of said shaft 10 is secured in any suitable well known manner a cap or sleeve 12 carrying suitable lugs or projections 14 to which the blades 13 of a fan 2 are rotatably secured. Upon the opposite end of the shaft 10 is loosely mounted a sleeve 15 which is connected to the blades 13 of the fan by means of links 16 or the like. A spring 17 encircling the shaft 10 is provided between the cap or sleeve 12 and said sliding collar 15, while a collar 18 upon the shaft 10 limits the movement of the collar 15 and regulates the expansion of the spring 17. A rod 19 is secured to the collar 15 and is attached to a rod 22 as shown at 23.

Said rod 22 is secured to a spark regulating lever 24 which is also connected at 25 to a lever 26 which is connected in turn to a throttle valve of the engine which is placed in the inlet pipe 27. The manual connections for operating the throttle valve are mounted on the steering post of the machine in the customary manner.

When the engine is in its state of rest the spark lever at 24 is in the position shown in Fig. 1. As soon as the engine is started the shaft 10 is revolved and the centrifugal

force acting upon the collar 15 tends to compress the spring 17 for throwing the blades 13 outwardly and pulling the collar 15 toward the right so that also the rod 19 is moved toward the right and is thrown in its vertical position, shown in Fig. 2. By this movement of the rod, the rod 22 connecting the spark at 24 with the steering gear, is moved toward the left. The more speed is gained by the engine the farther will the wings 13 of the fan fly apart and the greater is the timer's adjustment of the spark advanced. It is clear that now the driver can control the working of the entire engine from one lever controlling the gas throttle and the sparkler so that only one operation is necessary to change the speed of the engine to a desired degree, by operating a combined throttle and spark lever on the steering post. Such combined throttle and spark lever would be operated to set the spark and throttle at the desired place for starting whereupon, after the engine had begun to run on its own power, the throttle and spark would be automatically advanced by the action of the fan as previously described. When, however, it is desired to slow the engine, the combined control lever just mentioned could be operated by hand to assist the spring 17 in opposition to the action of the fan blades and thus throw the throttle and sparkler in position for slow running.

It is clear that changes may be made in the arrangement and general form of the parts and their mutual operation without departing from the spirit and scope of the present invention.

I claim:

1. A spark adjuster for explosive engines comprising a shaft connected to the engine shaft, a fan having foldable wings upon one end of said shaft, a sleeve upon said shaft to which the foldable wings of said fan are pivotally connected, links connected to said wings, means upon said shaft for regulating the outward movement of said links, and means for controlling said regulating means.

2. A spark adjuster for explosive engines comprising a shaft connected to the engine shaft, a fan upon one end of said shaft having foldable wings, a sleeve upon said shaft to which the foldable wings of said fan are pivotally connected, means upon said shaft for regulating the outward movement of said links, and means for controlling said

regulating means synchronously with the speed controlling means of the engine, substantially as described.

3. A spark adjuster for explosive engines comprising a shaft operatively connected to the engine shaft, a sleeve at the end of said shaft, a fan having its wings pivotally secured to said sleeve, a coil spring encircling said shaft, a movable sleeve upon said shaft adapted to be displaced by the actuation of said spring by centrifugal force, means for connecting said movable sleeve with the spark regulating lever of the engine, and means for connecting said lever with the fuel controlling means, substantially as described.

4. A spark adjuster for explosive engines comprising a shaft operatively connected with the engine shaft, a fan having 20 wings pivotally secured to a sleeve upon the

end of said shaft, a coil spring encircling said shaft, a movable sleeve upon said shaft displaceable by the operation of said spring, means for connecting said sleeve with the wings of said fan, means for connecting said movable sleeve with the speed regulating lever of the engine, means for limiting the movement of said slideable sleeve, and means for connecting said spark regulating lever with the speed regulating lever for controlling the sparking synchronously with the speed of the engine, substantially as described.

In testimony whereof I affix my signature in presence of two witnesses.

JOSEPH PETER GERING.
